UNITED STATES PATENT OFFICE.

ALBERT SANDEL, OF CHICAGO, ILLINOIS, ASSIGNOR OF ONE-HALF TO FRANK SCHOLZ,
OF CHICAGO, ILLINOIS.

GAME APPARATUS FOR MULTISIX-COLOR GAMES.

Application filed November 19, 1925. Serial No. 69,982.

My invention comprises a game apparatus, which includes a game-board or chart with a plurality of enclosures, preferably in the form of concentric rings, with groups or sets, preferably in the form of curved rows, of play-circles or stations within each ring, and certain of said play-circles or stations being provided in particular colors which represent particular values in the respective rings or enclosures, and the apparatus further includes play-pieces or counters which contain notations, such as numbers and letters, and which are used in connection with the play-circles or stations on the game-board; and the object is to provide such a game apparatus which will afford considerable amusement and also exercise for the intellect of the players.

Other objects will appear hereinafter.

20 The invention consists in the combinations and arrangements of parts hereinafter described and claimed.

The invention will be best understood by reference to the accompanying drawings 25 forming a part of this specification, and in which,

Fig. 1 is a plan view of the game-board: and

Fig. 2 is a detail view of several of the 30 play-pieces or counters.

The form of game apparatus illustrated in the drawing comprises a game-board of any suitable material and size, which I call the "Multisix board," and a plurality of 25 play-pieces or counters of various colors and bearing various notations, which board and play-pieces together form the game apparatus of "Multisix." This game-board, as shown in Fig. 1 of the drawings, contains 40 a plurality of concentric enclosures or rings, the inner ring 10 of which has a plurality of points 11 extending from its circumference substantially forming a star.

A second ring or enclosure 12 encircles 45 said center ring 10, and within the boundaries of this second ring are six small play-circles 13 arranged in a curving row or group, said circles being separated by small spaces. Between the first and last play- 50 circle of the row or group is a frame or design 14 upon which are printed or marked

the numbers 90, 60, and 30, as shown in the drawings.

A third ring or enclosure 15 encircles the 55 second ring or enclosure 12, and within the boundaries of this third ring are twelve play-circles 16 separated by small spaces, the circles forming two curving rows or substantially semi-circular groups of six each, 60 the two rows being separated by two designs 17. Upon each design are printed or marked the numbers 75, 50 and 25, as shown in the drawings.

A fourth ring 18 encircles the third ring, 65 and within the boundary of this fourth ring are eighteen play-circles 19, separated by small spaces, the circles forming three curving rows or groups of six each. Said rows are separated by three designs 20, upon each 70 design are printed or marked the numbers 60, 40 and 20, as shown.

A fifth ring 21 encircles the fourth ring 18, and within the boundaries of this fifth ring are twenty-four play-circles 22, which 75 are separated by small spaces, the circles forming curving rows or groups of six. These rows are separated by four designs 23 upon each design are printed or marked the numbers 45, 30 and 15, as shown. Upon 80 two of the play-circles 22' in this ring is printed or marked the number "1," each being at the head of one of the rows of six play-circles and each of the numbers having a different color, one of said numbers being 85 colored the same as the number "1" of the group of four numbers upon the succeeding circumscribed ring, described below, the other number being colored as the number "3" of said group of numbers in that circumscribed ring. One number "1" heads 90 the third row of play-circles.

A sixth ring 24 encircles the fifth ring 21, and within the boundaries of this sixth ring are thirty play-circles 25, separated by small 95 spaces, the circles forming curving rows or groups of six each, which rows are separated by five designs 26, as shown; and upon these designs are printed or marked the numbers, 30, 20 and 10, as shown in the drawings. 100 Upon the first four of the play-circles of one of the rows of six in this ring are marked or printed the numbers as follows: No. "1,"

- upon the first circle 27, which is printed or marked in a certain color thus establishing or providing the color of this row or group of circles; while upon the second circle 28 5 is marked or printed the number "2" in a color different from the color of No. "1," and this establishes the second color of the row; upon the third circle 29 is printed or marked the number "3," in a color which is 10 different from either of the colors of No. "1" or No. "2," thereby establishing the third color of the row; and upon the fourth circle is printed or marked the number "4," preferably in the same color as No. "3." 15 This ring also contains, upon the first three of the play-circles of another row of six, the printed or marked numbers as follows: No. "1" upon the first circle 31, printed or marked in a color which is preferably the 20 same as Nos. "3" and "4" of the other row in this ring, as described above; and upon the second circle 32 in this row is printed or marked No. "2" in a color which is the same as No. "1" of the other row of the ring 25 mentioned above; and upon the third circle 33 is printed or marked No. "3" in a color which is preferably the same as No. "2" of the other row in this ring, as described above. The group of four numbers is 30 marked upon the first row of play-circles, and the group of three numbers is marked upon the third row of play-circles in this sixth ring 24. The seventh ring 34 encircles the sixth ring 24, and within the boundaries of this 35 seventh ring are thirty-six play-circles 25, which are separated by small spaces, and these circles form curving rows or groups of six each, which rows are separated by six designs 36, upon which designs are printed or marked the numbers 15, 10, and 5, as shown. Upon the first and second of the play-circles of one of the rows of six in this ring are printed or marked Nos. "1" and "2" 40 in a color which is preferably the same as No. "2" of the group of four members in the sixth ring; and upon one of the play-circles of one of the rows of six in this ring is printed or marked the number "1" 45 in a color which is preferably the same as the numbers "1" and "2" of the other row in this ring. The number "1" heads the first row of this seventh ring, and the numbers "1" and "2" head the fourth row of 50 this ring. The game of "multisix", or the game 55 played with my apparatus, is adapted to be played by a plurality of players, from two to six players. 60 The play-pieces which I provide are small disks or counters 37, upon which certain notations are printed or marked, and some of these play-pieces have the numbers "1" to "6" inclusive thereon, one number on each counter or disk. There are sixteen counters

of each number, provided in three sets, each set appearing in a different color, the total sets of numbers appearing in quantities and colors as follows:

Quantity.	Number.	Color.	Quantity.	Number.	Color.
Six.	1	Green.	Six.	2	Black.
Five.	1	Black.	Five.	2	Green.
Five.	1	Red.	Five.	2	Red.
16			16		
Six.	3	Red.	Six.	4	Green.
Five.	3	Black.	Five.	4	Black.
Five.	3	Green	Five.	4	Red.
16			16		
Six.	5	Black.	Six.	6	Red.
Five.	5	Green.	Five.	6	Black.
Five.	5	Red.	Five.	6	Green.

There are also six play-pieces 38 marked "H", which are intended to designate "high" and are provided in sets of two play-pieces, each set appearing in a different color; the three shades of colors being the same as the three shades on the number-bearing play-pieces 37. There are also twelve play-pieces 39, marked with a small circle in the center, which pieces are known as "low" or "substitutes"; and these pieces are all of one color, any desirable color.

One of the players is the score-keeper and dealer, and deals to each player nine play-pieces from a small cloth bag or the like, preferably dealing three at a time. After the first play, that is, after each player in his turn has placed his play-piece on the game board the dealer deals each player another counter or disk and so on.

It is intended that when two players play they use fifty disks; when three players play, they use seventy-five disks; four players use one hundred disks; five players use one hundred and ten disks; and six players use one hundred and fourteen disks or all the disks.

Each player, in his turn, may place any one of his disks or counters on any one of the small circles in the curved rows of six small circles in any of the rings, if the number upon his disk fits into the rotation of the numbers which are printed upon a certain few of the rows of small circles upon the play-board or game-board, and he receives the points which are due him, by playing in either the first, the second, or the third color. For example,—in a row where the first small circle has the number "1" in green color, the second circle has the number "2" in black color, and the third small circle has the number "3" in red color, as shown in the sixth row 24,—should the player want to play onto this row, he must play the following consecutive number, which is number "4" and if of black color, he plays in the second color of this ring and receives the sec-

ond color of this ring and receives the sec-

ond highest score marked in this ring, which is twenty, then if the next player should place a disk or counter with a black number "5" onto this row, he also plays in the second 5 color and receives twenty points, which are due the second color of this ring. The third player in his turn may place a green number "6" onto the last or sixth small circle of this row, and thus plays in the first color 10 and receives the highest score marked for that ring, or thirty.

Should a player have a disk or counter with a number "1," he in his turn may place the disk upon a play-circle which bears 15 a star and which is the first of a curved row of six small circles and with the color on said disk or counter he may establish first color for that row and consequently he may receive the highest score marked for that 20 ring; then if the next player plays the number "2" in the same color he also receives the highest score, as he is also playing in the first color. The third player may play a disk with a number "3" of a different color 25 than the numbers "1" and "2," and thereupon establishes the second color of the row and receives the second highest score marked for that ring. The fourth player, playing a disk with a number "4" of a color different 30 from the colors of the numbers "1," "2," and "3" plays in the third color and receives the third or low score marked for the ring.

No matter which row the player plays onto, if he plays a numbered disk, he must 35 follow the rotation of the row and place his disk where the number thereon belongs, so that the numbers on each curved row follow in consecutive order, counting "1" from the circle with the star or from the printed 40 number "1" on the first play-circle of the row.

In case a player has no number "1" and does not want to play into any open row 45 which has a printed or marked disk with a number already placed thereon, but if such player has a "low" disk or "substitute" disk he may place said "low" or "substitute" disk onto any established row and receive the lowest score, which is five points, no matter 50 which row or ring he may play the "low" disk onto. Should he have no "low" disk or no disk with an "H" or "high," he must place one of his play-circles on the star 55 in the center of the game-board and he thereby loses thirty points.

A play-piece marked "H" may be placed upon any play-circle onto any row in consecutive order or rotation, and counts one hundred points with additional points which 60 the ring allows for the first, second, or the third color, in whichever position said "H" disk is placed in said row.

An "H" play-piece can be placed into a play-circle with a star, to head the row and establish color, but a "low" play-piece can-

not head the row. The placing of a "high" disk, also the placing of a "low" disk does not break the rotation for the numbered disks, but takes the place of the next number, for example,—if a "high" disk or if 70 a "low" disk has been placed onto a circle where a number "3" ought to be, then the next player, who plays onto the row, must place the following consecutive number or number "4" in the next circle. 75

Play-pieces, in order to receive points, must be laid open to all players' views which may be done any time during the game, or at the latest right after the deal which gives each of the players his last play-piece. 80 These final play-pieces then produced score as follows: four of a number and color score one hundred and sixty points; five of a number and color two hundred and fifty; six of a number and color score three hundred and sixty points; six of a number and mixed color score ninety points, if the six are still intact each additional play-piece scores thirty points more; six play-pieces with the consecutive numbers from one to 90 six and of the same color score one hundred and eighty points.

A player having four play-pieces of a same number and color placed open upon the table, upon receiving the fifth one of the same number and color adds ninety points to his score, and should he receive the sixth he adds one hundred and ten points; he also adds one hundred and ten points if he had laid down five pieces open and later 100 receives the sixth one of the same number and color.

When the players each have three play-pieces left they then play no longer onto the rows of the game-board, but they count 105 the score then on the last three play-pieces and add that same to the score obtained during the playing of the game. "Low" or "substitutes" on the last three disks do not score; and the highest score wins the game. 110

While I have illustrated and described the preferred form of construction for carrying my invention into effect, this is capable of variation and modification without departing from the spirit of the invention. 115 I, therefore, do not wish to be limited to the precise details of construction set forth, but desire to avail myself of such variations and modifications as come within the scope of the appended claims. 120

Having described my invention what I claim as new and desire to secure by Letters Patent is:

1. A game apparatus comprising a game-board having a plurality of enclosures with 125 groups of play-circles or stations thereon, several of said groups containing circles or stations with certain colors displayed thereon which colors denote certain values, and play-pieces with corresponding colors adapt- 130

- ed to be placed on said stations to score certain values.
2. A game apparatus comprising a game board having a plurality of concentric enclosures containing groups of play-circles or stations thereon, several of said groups containing stations with certain colors and with numbers thereon, said colors representing certain values, and play-pieces with corresponding colors and with numbers thereon to be placed in consecutive order on the play-circles for scoring certain values in accordance with the colors on said play-pieces.
3. A game apparatus comprising a game-board having a plurality of concentric rings forming annular enclosures provided with groups of play-circles, one of said groups containing several numbered circles with consecutive numbers thereon, and play-pieces with numbers thereon to be placed on the group of circles so as to consecutively follow the numbers provided on the numbered circles in said group.
4. A game apparatus comprising a game-board having concentric annular enclosures with curved rows of play-circles thereon and with frames including score numbers placed between said rows of circles, and play-pieces to place on said play-circles for obtaining the scores marked in said frames.
5. A game apparatus comprising a game-board having a plurality of annular enclosures with groups of play-circles thereon, several of said groups containing play-circles bearing numbers and certain colors which represent certain values.
6. A game apparatus comprising a game-board having a plurality of annular enclosures with groups of play-circles thereon, several of said groups containing play-circles bearing numbers and certain colors which represent certain values, and play-pieces with varying numbers and in various colors, to play on said circles for obtaining certain scores.
7. A game apparatus comprising a game-board containing a plurality of concentric circles which form concentric annular spaces, curved groups of circles in said spaces, several of said groups having circles containing certain colors and numbers and other groups including stars, each being placed on the first circle of the group, play-pieces with numbers and colors to place in consecutive order on said circles, and frames located between the groups of circles and having several numbers thereon to denote the values of the colors on said circles and thereby the scores obtainable by playing the certain colored and numbered play-pieces on the various circles.
8. A game apparatus comprising a game-board containing a plurality of concentric annular spaces, groups of play-circles in said spaces, several of said groups having circles containing certain colors and numbers and other groups including stars, each placed on the first circle of the group, play-pieces with numbers and colors to play on said circles, other play-pieces with colors and notations thereon to indicate a "high" or "low" score, and frames with numbers thereon located between the groups of circles to denote the values of the colors and the scores obtainable therewith by playing the certain colored play-pieces on the circles.
9. A game apparatus comprising a game-board containing a plurality of concentric circles forming concentric annular spaces, several of said groups having stars on the first circle and other groups having one or more numbers in consecutive order on the circles beginning with the first circle and bearing certain colors, play-pieces with numbers and colors to form several complete sets of consecutive numbers in the various colors to play in consecutive order on said circles, other sets of play-pieces with notations thereon to indicate a "high" or a "low" score, frames provided between the groups of circles in each annular space and having several numbers therein to denote the various values for the colors in the respective enclosures, said apparatus being adapted for playing a game in which the numbered and colored play-pieces are placed consecutively on the circles in each group, and in which the colors on said numbered circles establish certain colors and scores in that group, while in the group beginning with a star the color of the play-piece with number "1" establishes the first color and the highest score for that group, and the nearest following play-piece that appears in a different color establishes the second color and score for that group.
- In testimony whereof I have signed my name to this specification.

ALBERT SANDEL.
